UNITED STATES PATENT OFFICE.

VICTOR WILLOUGHBY, OF JEFFERSONVILLE, INDIANA, ASSIGNOR TO AMERICAN CAR AND FOUNDRY COMPANY, OF ST. LOUIS, MISSOURI, A CORPORATION OF NEW JERSEY.

CAST-STEEL DOOR-FRAME.

1,097,959.

Specification of Letters Patent. Patented May 26, 1914.

Application filed September 17, 1913. Serial No. 790,295.

To all whom it may concern:

Be it known that I, VICTOR WILLOUGHBY, residing at Jeffersonville, Clark county, Indiana, and being a citizen of the United States, have invented certain new and useful Improvements in Cast-Steel Door-Frames, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a side elevation of the side door reinforcement casting, showing at the left of the door opening center line a portion of the car side framing, the door post cover, the door header and the threshold. Fig. 2 is a plan view of said casting, the left hand half disclosing the side plate in its relationship to the casting. Fig. 3 is a horizontal section along the line 3—3 of Fig. 1. Fig. 4 is a vertical section through the door opening shown to the left of the center line in Fig. 1. Fig. 5 is an end elevation of the right hand end of the casting shown in Fig. 1; and, Fig. 6 is a horizontal section along the line 6—6 of Fig. 1.

My invention pertains to load carrying side door reinforcements for railway vehicles, such as baggage, postal or express cars, and has especially for its object a cast frame composed partially of door posts integrally connected at the bottom with a door sill having extensions which constitute a side sill reinforcement, and at the top with a door lintel also having extensions and serving as a side plate reinforcement, the reinforcements projecting outwardly from the door posts far enough to fully develop their bending stresses at said door posts, rendering additional reinforcement to stiffen the car side framing at the door opening unnecessary.

The total length of the side sill and side plate reinforcements, which is to say, the total length of the casting, depends entirely upon the construction of the car, the size of the door opening and the load the car will

carry, which elements determine the bending moment of the reinforcement members.

Another object of this invention is to so form the door posts that they may support on the exterior wooden fillers or furrings adapted to provide places of attachment for grab irons, cinder guard brackets, door fasteners, and the like, if desired. As an extension of this advantage, the door posts are also adapted to have attached to them furrings exposed to the interior, to which may be applied the inside lining of the car.

A further object is the provision of integrally cast gussets at the corners of the junctions of the door posts and the side sill reinforcement, and, also, of the door posts and side plate reinforcement, the proper gussets being provided with attachment means for the diagonal braces auxiliary to the gussets themselves. The gussets and the auxiliary attaching elements permit the side door reinforcement casting to be included in the car side framing. Additional means integral with the door posts exist intermediate the upper and lower ends of the latter for securing the belt rail to the side door reinforcement casting.

It is also an object of this invention to present as an integral part of the casting, a suitable support for the door track, and still further a position, at the top of the side sill reinforcement and between the door posts, for the reception of the usual threshold plate, and an offset in said side sill reinforcement to accommodate the portion of the side sill contacting therewith.

A feature of the upper inner corners of the door opening is that the casting is so molded as to leave ample clearance for the joints of the door post cover and door header when they are inserted into the door opening.

Another object is to so construct the side sill reinforcement that it will offer no obstruction to the attachment of floor bearers.

Considering the details of the drawings, the elements of the side framing of the car are denoted by letters in which—

A indicates the side sill of a car underframe, which in this case, is shown as an angle iron with its horizontal leg lowermost. The side plate B of the superstructure, is also an angle with its horizontal leg uppermost, and connecting the side plate B to a gusset C, the latter being riveted to side sill A, is a side post D. To the gusset plate

C is also riveted the lower end of a diagonal brace E, which is a standard angle, and extends obliquely upward until it engages a gusset which is an integral part of the side door reinforcement casting. The connection of the diagonal brace to this gusset will be referred to later on.

A channel F, constituting a part of the belt rail, which runs the length of the car 10 and is interrupted only by the door opening, is shown as riveted at one end to the side post D at a point intermediate the ends of said side post, and at the other to the casting.

15 Near the upper extremity of the side post D is the letter board angle G to which the lower edge of the usual letter board is attached.

The side sill reinforcement 1 is of materially greater length than the width of the door opening, its ends 2 extending outwardly from the door posts 3. In the type 20 of casting here illustrated, the side sill reinforcement 1 is of uniform cross section in its central portion, *i.e.*, between the door posts 3, but the top edge of those parts of the vertical leg included in the end portions 2 inclines downwardly as it proceeds 25 toward the outer extremities of said end portions. The horizontal leg of the side sill reinforcement extends to an altitude which is but little less than the upper surface of the floor 4, the small difference being such as is necessary to accommodate a threshold 30 plate 5 which is provided with ribs 6. These ribs resting upon the horizontal leg of the side sill reinforcement sustain the threshold plate 5 so that it forms practically a continuation of the floor.

40 Outside of the door posts 3, the horizontal leg of the side sill reinforcement inclines downwardly in accordance with the inclination of the top edge of the vertical leg, and also tapers laterally toward this leg.

45 Attention is directed to the central portion of the side sill reinforcement 1, where it will be seen that the horizontal leg extends outwardly beyond the plane of the parts of the vertical leg in the ends 2. Here 50 the upper part of the vertical leg is bulged out at 7 forming an abutment for the outer roll edge of the threshold plate and a contact surface for the sheeting, and permits the width of the horizontal leg to agree with the 55 depth of the door posts 3.

Below the bulged portion 7 the vertical leg of the side sill reinforcement is inset and remains so throughout its length, thereby permitting the outer face of the vertical leg 60 of the side sill A to be in the same plane as the bulged portion 7 of side sill reinforcement, the outer surfaces of the door posts 3 and the side plate reinforcement 8, and the inner surfaces of the side sheet of the car, 65 which is indicated in dot and dash lines at

H in Figs. 3 and 6 and in dotted lines in Fig. 4.

At 9 and 10 are shown, in the outer angles formed by the intersection of the lower end of the door posts 3 and the top of the side sill reinforcement 1, gussets which are integrally cast with the parts mentioned. Similarly, in the outer angles formed by the intersection of the upper ends of the door posts 3 and the under side of the side plate reinforcement 8 are located other gusset plates 11 and 12, also integral parts of the side door reinforcement casting. Extending outwardly from the door posts, all these gussets are immediately bent back into the plane of the inset portion of the vertical leg of the side sill reinforcement. The reason for this is to bring the faces of those gussets which are to contact with the diagonal braces E into the same plane as the contacting faces of said diagonal braces. As seen in Fig. 5, this brings the gusset 10 into the same vertical plane as the vertical leg, exclusive of the bulged portion 7, of the side sill reinforcement 1, and gussets 9, 11 and 12 occupy the same plane for the same reason. From gussets 11 and 10 extend inwardly lugs 13 and 14.

Hereinbefore, the diagonal brace E was described as being riveted at its lower end to gusset plate C, which in turn is secured to the side sill A. The upper end of this brace is riveted to the cast gusset 11, against the inner face of which the outer leg of angle E rests. The inwardly projecting leg of the diagonal brace bears against the under-surface of lug 13 of the gusset 11 and is riveted thereto. Thus said diagonal brace firmly connects this part of the casting to the side framing.

The side sill reinforcement is rigidly connected to the side sill A by rivets, the inset portion at the center of the vertical leg of the former being in the same plane as the parts of the vertical leg in the ends 2, thus presenting a continuous contacting surface to the side sill A, while the side plate reinforcement is strongly riveted to the side plate. The end portions 2 of the side sill reinforcement, and 15 of the side plate reinforcement are of sufficient length to fully develop their bending stresses at the door posts so maintaining sufficient stiffness in the side framing at these points.

Letter board angle G is riveted adjacent its end to the outer face of the integrally cast gusset 11, its horizontal leg being cut away near the gusset to permit its vertical leg to contact with it. Angle G extends to and beyond the side post D, in fact, to the car end. At the side post the horizontal leg of the letter board angle is again cut so that the two may be riveted together.

Projecting outwardly from each door post 3 at a point intermediate its ends is a wing

16, (see Fig. 1), applied to which is the belt rail F, which is also attached to the side post D.

The side framing which has been omitted at the right in Fig. 1 is substantially the same as that shown at the left, the integral gusset 10 carrying a lug 14. The diagonal brace associated with this side of the door has its lower end attached here in the same manner that the upper end of brace E was attached to gusset 11 and lug 13. The letter board angle is applied to gusset 12, and the belt rail to wing 16.

For hanging the door 17, through the agency of hangers 18, the horizontal leg of the side plate reinforcement affords a support for the track rail 19, upon which the hangers roll, and the track may be riveted or bolted thereto, as shown in dot and dash lines in Fig. 4; or a furring may be attached to said horizontal leg and the track secured to it.

As clearly illustrated in Fig. 4, it will be seen that the vertical leg alone of the side sill reinforcement is attached to the side sill A, leaving the horizontal leg of the latter free to receive the end of the floor bearer J, the latter being capable of connection to the side sill through the employment of a connection plate K.

The door posts 3 have a cross section which is a combination of a structural Z and an angle. This allows the reception of wooden fillers or furrings 20 by the door posts, facing the exterior of the car, and other furrings 21 exposed to the interior. Wood screws 21 pass through furrings 21, through apertures in door posts 3 and into furrings 20, securing both furrings firmly to the door posts 3. See particularly Fig. 6.

Door cover posts 23 inclose the door posts 3 and furrings 20 on the exterior. To the furrings 20 may be secured by machine screws, grab irons, cinder guard brackets, door fasteners or similar attachments, if desired, the screws, of course, penetrating the cover posts. The inside lining of the car may be applied to the inside furring 21.

Cover posts 23 and the door header 24 are mitered at the upper corners of the door opening and welded together and the corresponding corners in the side door reinforcement casting are offset or recessed at 25 to provide ample clearance for the welded corners of the cover posts and the header, which are applied as one frame.

The side door reinforcement casting becomes a part of the side framing of the car in which it is installed, and the side sill reinforcement and the side plate reinforcement prevent any weakening of the framing at the door opening particularly as any tendency to vertical displacement will be automatically and proportionately opposed by the bending moments set up in the end portions

of said reinforcements, the maximum bending stress occurring at the door posts. The integrally cast gussets which, as hereinbefore stated, are bent into the plane of the inset portion of the vertical leg of the side sill reinforcement and belt rail wings receive the adjacent ends of the commercial structural shapes employed in the framing in such manner that none of the shapes interfere with each other, or with the elements of the casting, and so as to present surfaces for the attachment of the side sheeting.

The usual fittings can be applied to the door post, which is neatly finished by the cover posts. The light sheet metal frame comprising the cover posts and door header is easily applied, as is the threshold plate and the door track, and the inside lining finds a proper and secure termination at the door opening.

I claim—

1. In a car side having furrings for an inside lining and wooden door post fillers, an integral casting comprising door posts connected at their upper extremities by a side plate reinforce extending beyond said posts, and at their lower extremities by a side sill reinforce extending beyond the door posts, said door posts having recesses in their inner and outer sides for the reception of said furrings and fillers, and those portions of said side plate reinforce and side sill reinforce extending beyond said door posts each being capable of developing a maximum bending stress within itself adjacent one of said door posts.

2. In a car side having side framing, furrings for an inside lining and door post fillers, an integral casting comprising door posts having a combined Z and angle shaped cross section adapted to receive and support said furrings and fillers, a side plate reinforce extending beyond said door posts, a side sill reinforce also extending beyond the door posts, the end portions of said side plate and side sill reinforces each being capable of developing within itself a maximum bending stress at one of said door posts, and means for attaching elements of the car side framing to said casting.

3. In a car side having side framing, furrings for an inside lining and door post fillers, a cast metal door frame comprising door posts having a combined Z and angle shaped cross section adapted to receive and support said furrings and fillers, a side plate reinforce of angular cross section extending beyond said door posts and serving also as a door track support, a side sill reinforce of angular cross section extending beyond the door posts, the end portions of said side plate and side sill reinforces each being capable of developing within itself a maximum bending stress adjacent a door post, and means for securing the casting to the struc-

- 4
- tural elements of the car side framing, certain of the surfaces of the casting presenting riveting areas, and all the parts being integral.
5. In a car side, a unitary casting comprising door posts recessed to facilitate the insertion of cover posts and a door header, and adapted to support filler and car lining furrings, a side plate reinforce extending 10 beyond the door posts and also serving as a door track support, a side sill reinforce extending beyond the door posts, those portions of said side plate and side sill reinforces which extend beyond the door posts each being capable of developing a maximum bending stress within itself adjacent one of said door posts.
5. In a car side having side framing, a unitary casting comprising door posts recessed to facilitate the insertion of cover 20 posts and a door header, and adapted to support filler and car lining furrings, a side plate reinforce extending beyond the door posts and also serving as a door track support, a side sill reinforce extending beyond the door posts, the end portions of said side plate and side sill reinforces each being capable of developing a maximum bending stress adjacent one of said door posts, and 25 gussets and wings for attaching to said unitary casting elements of said side framing.
6. In a car side, an integral casting including door posts, a side sill reinforce extending beyond said door posts, adapted to be secured to the side sill of a car and whose vertical dimensions increase from its ends 30 toward and substantially to said door posts to establish the desired altitude of a threshold plate, each end portion of said side sill reinforce being capable of developing a maximum bending stress adjacent one of 35 said door posts.
7. In a car side having a side framing, an integral casting comprising door posts, a side plate reinforce and a side wall reinforce, each reinforce extending beyond the door posts and the end portions of each reinforce each being capable of developing a maximum bending stress at one of said door 45 posts, the vertical dimensions of said side sill reinforce increasing from its ends toward and substantially to said door posts to establish the desired altitude of a threshold plate, and means for attaching elements of the car side framing to the casting.
8. In a car side, an integral casting comprising door posts adapted to embrace and support furrings on two sides of each post and being recessed to facilitate the insertion 60 of cover posts and a door header, and a side plate reinforce having end portions extending beyond said door posts, each of which is capable of developing a maximum bending stress at one of said door posts.
- 85
9. In a car side having side framing, an integral casting comprising door posts adapted to embrace and support cover post fillers and car lining attachment furrings and being recessed to facilitate the insertion 70 of cover posts and a door header, a side plate reinforce extending beyond said door posts and serving also as a door track support, a side sill reinforce extending beyond said door posts, the end portions of the side 75 plate and side sill reinforces each being capable of developing a maximum bending stress at the door posts, and means for attaching elements of the car side framing to the casting.
